DESIGN FOR A SPOON OR SIMILAR ARTICLE

Frank S. Trumbull, Providence, R. I.

Application June 27, 1935, Serial No. 57,424

Term of patent 3½ years

To all whom it may concern:

Be it known that I, Frank S. Trumbull, a citizen of the United States of America, residing at Providence, county of Providence, State of Rhode Island, have invented a new, original, and ornamental Design for a Spoon or Similar Article, of which the following is a specification, reference being had to the accompanying drawing, forming a part thereof.

Fig. 1 is a front elevational view of a spoon or similar article showing my new design; and Fig. 2 is a longitudinal sectional view through the center of the spoon handle, of the same.

This design consists of round scrolls and tracer lines forming an outline for the spoon with the tracer lines broken by a scroll tip converging to the middle to relieve the monotony of the tracer lines combined with a pattern of American roses and rose leaves which are in a wreath effect passing along the outside edge of the handle at its upper end and leaving a central plain shield.

I claim:

The ornamental design for a spoon or similar article substantially as shown and described.

FRANK S. TRUMBULL.
